UNITED STATES PATENT OFFICE.

MOSES WILKES, OF TRENTON, NEW JERSEY.

CUT-OFF FOR LOCOMOTIVE-ENGINES.

SPECIFICATION forming part of Letters Patent No. 628,569, dated July 11, 1899.

Application filed August 17, 1898. Serial No. 688,790. (No model.)

To all whom it may concern:

Be it known that I, MOSES WILKES, a citizen of the United States, residing at Trenton, in the county of Mercer and State of New Jersey, have invented certain new and useful Improvements in Cut-Offs for Locomotive-Engines; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to certain new and useful improvements in locomotive and other quick-running engines, and more particularly to means for cutting off the steam promptly to produce the best effects in the movement of the valves and to secure economy of steam and fuel. As far as I am aware locomotives as at present constructed involve the use of the link-motion—such, for instance, as that known as the "Stephenson" link-motion—which is used principally for the purpose of reversing the engine and which at the same time may be so employed and used as to give a distribution of steam in which the cut-off is earlier than in full gear and the expansion and compression are greater. This link-motion, while it is one of the earliest, is still the most usual form now in use; but its action as a cut-off is not entirely satisfactory for reasons well known to engineers.

My invention has for its object to provide a locomotive or other quick-running engine with a cut-off mechanism which shall be simple in construction and effective in operation; and with these ends in view my invention consists in the construction and arrangement of cut-off mechanism hereinafter more fully described.

In order that those skilled in the art may fully understand my invention, I will proceed to describe the construction and operation of the same, referring by letters to the accompanying drawings, in which—

Figure 1 represents a side elevation of my improved cut-off mechanism connected to part of a locomotive to illustrate my invention. Fig. 2 is a side elevation of the opposite side of Fig. 1 and partly in section. Fig. 3 is a top

or plan view of the same. Fig. 4 is an enlarged cross-section on line $\alpha\alpha$ of Fig. 1.

Similar letters of reference indicate like parts in the several figures.

A is the main valve, with the usual steam-ports a and exhaust-port b , all of the ordinary construction and seated on the valve-seat of the cylinder. Upon the back of the main valve is seated the cut-off valve B, made in two parts or blocks B' B', to one of which the hollow valve-stem c is attached, while the other one is provided with a stem d , passing through the hollow stem c . Each of these valve-stems is provided with a lug e , to which the eccentric-rods f are pivoted, and said rods are connected at their inner ends to the eccentrics g .

The reciprocation of the main-valve stem l , and consequently the main valve A, is effected by the usual eccentrics H H on the main shaft and the link G , and as this main-valve stem l is rigidly attached to the block I, pivoted between the lower ends of lever C, while the cut-off valves B' are eccentrically connected with the upper end of said lever C, it will be seen that the latter has a double motion—viz., a general longitudinal motion caused by the reciprocation of the main-valve stem and a vibrating motion on the pivot-shaft h , caused by the action of the eccentric E on the main shaft and the mechanism intermediate of said eccentric and the upper end of lever C, and consequently the cut-off of the steam is effectively controlled. This lever C is made of two parts, as clearly shown.

The upper ends are connected by a short shaft which constitutes a pivotal connection for one end of a link i , the other end of which is pivotally connected to a crank D on the shaft j , which is journaled in a bearing on the support k . To this shaft j is secured another crank D' , diametric to the crank D , and the outer end of the crank D' is connected through the medium of a rod E' with an eccentric E on the main shaft. The lower ends of the two parts of the lever C embrace a block I, (see Fig. 4,) which vibrates upon a pivot-bolt h , and the main-valve stem l passes through and is rigidly secured to the block I. Near the upper end of the lever C are arranged two short shafts g' , carrying each an eccentric g , to which the inner ends of the

eccentric-rods f are respectively attached, the outer ends of said rods being connected, as above stated, to the lugs e on the two-part valve-stem $c d$. Each of the shafts g' is provided with a gear-wheel n , intermeshing with each other, and one of said shafts is also provided with a crank, connected through the medium of a rod K with a bell-crank lever L , and by means of which and the intermeshing gears $n n$ the two shafts g' are caused to rotate and the eccentrics g are caused to approach or recede from one another, as desired, and consequently the throw of the cut-off valves $B' B'$ is controlled in an obvious manner.

15 The main-valve stem l is connected at one end to the main valve A and at the other end to a link-block by a pivot-bolt m . This block moves in the curved slot in the link G of ordinary construction, as shown at Fig. 1. The link is connected by a rod G' to an ordinary bell-crank lever, and the travel of the main valve is controlled or changed in the usual manner.

The operation is as follows: The main valve 25 is set in the usual way by adjusting the eccentrics H on the shaft to their proper position for the proper amount of travel of the valve. By raising or lowering the links G the travel will be varied as desired. The cut- 30 off is then placed so as to cut off the steam at the desired point. If it is desired to change the cut-off, the lever L is moved in either direction, which will cause the eccentrics $g g$ to be changed and, being connected to the valve- 35 stems c and d , will cause the blocks $B' B'$ to be moved closer together or farther apart, thus admitting the steam sooner or later, as desired.

What I claim as new, and desire to secure 40 by Letters Patent, is—

1. The combination with the ordinary eccentrics, link, and main valve and stem, the cut-off valves $B' B'$ having independently-movable stems, and a lever C , pivotally con-

nected at the lower end to the main-valve 45 stem and connected at the upper end through eccentrics g, g , to the cut-off-valve stems and through suitable intermediate mechanism with an independent eccentric E , on the main shaft, substantially as hereinbefore set forth. 50

2. The combination with the ordinary eccentrics, link, and main valve and stem, and with the cut-off valves $B' B'$ having independently-movable valve-stems, and a lever C , pivotally connected at its lower end to the main-valve stem, and at its upper end through eccentrics g, g , to the cut-off-valve stems, intermeshing gears n, n , on the shafts g', g' , and a crank on one of the shafts g' , and means for operating the said crank, substantially as 60 and for the purpose set forth.

3. In an engine, the combination with the main valve and stem operated by eccentrics on the main shaft, and cut-off valves operated primarily by an eccentric independently 65 of the main eccentric, the lever C , pivotally connected with the main-valve stem and through the medium of eccentrics and rods with the cut-off-valve stems, and adapted to reciprocate with the main-valve stem, and to 70 vibrate with the cut-off-valve stems as hereinbefore set forth.

4. In an engine, the combination of a main valve, a cut-off seated thereon and made in two parts, and a lever C , pivoted to the main-valve stem, said lever carrying gear-wheels n, n , and eccentrics connected by separate rods to lugs e, e , secured to the valve-stems of the cut-off, and arranged as described to cause the two parts of the cut-off to approach or recede from each other as and for the purpose set forth. 75

In testimony whereof I affix my signature in presence of two witnesses.

MOSES WILKES.
